UNITED STATES PATENT OFFICE.

WALTER S. MOODY, OF LYNN, ASSIGNOR TO THE GENERAL ELECTRIC COMPANY, OF BOSTON, MASSACHUSETTS.

COOLING ELECTRIC APPARATUS.

SPECIFICATION forming part of Letters Patent No. 516,829, dated March 20, 1894.

Application filed July 1, 1893. Serial No. 479,349. (No model.)

To all whom it may concern:

Be it known that I, WALTER S. MOODY, a citizen of the United States, residing at Lynn, in the county of Essex and State of Massachusetts, have invented a certain new and useful Improvement in Cooling Electric Apparatus, of which the following is a specification.

My invention relates to means for cooling electric apparatus, such as electric transformers, whereby excessive or dangerous heating of the coils in such appliances is prevented, and whereby the efficiency is increased by preventing increase of resistance to the current in the conductors forming its coils: and is especially adapted for use with large transformers or electrical apparatus, wherein the electric conductors are massed to form a bundle of considerable size, and are required to be surrounded by insulation capable of withstanding currents of moderate or high potentials; such insulation for current is nearly always a good insulator for heat also, preventing its ready escape from the coils. The coils or conductors are also surrounded by iron, in the laminæ forming the core of a transformer, which acts to prevent the free escape of the heat from the coils.

To carry out my invention, I establish a flow of cooling fluid or liquid through or about the transformer or other electric apparatus at a rate dependent upon and controlled by the flow of current through its coils; and to this end I employ a pump, a blower, or other fluid propelling apparatus, operated by a motor device whose speed or power is dependent directly or indirectly upon the current traversing the coils; in some instances, I employ conducting pipes or conduits leading to a casing surrounding the apparatus, or its coils, for conveying the fluid. Such pipes or conduits may also include a chamber for the cooling of the heated liquid or fluid coming from the transformer. Heretofore it has been proposed to cool such apparatus by a circulation of fluid brought about by the heat generated in the transformer itself, or by what might be termed a natural circulation or draft; such an arrangement is not economical or efficient, because it depends for its action upon the existence of the evil itself. In other words, a natural circulation or draft will not take place

until the air or other cooling medium has become so heated as to set up a circulation due to a difference in its specific gravity, or by its becoming lighter when heated. It is also not economical to maintain a vigorous circulation of the cooling medium through the transformer when it is lightly loaded, because such circulation is not then needed to carry away the heat generated. By my invention the cooling arrangements are so organized that the heating effect of a heavy current is anticipated, and the circulation of the cooling medium depends, not upon the existence of heat in the electric apparatus, but upon the flow of current which would, in time, generate undue heat therein; and, in the improved arrangement herein described, immediately such current begins to flow, the rate of circulation of the cooling medium is automatically accelerated and excessive heating prevented; and the rapidity of the circulation keeps pace with the increasing current, or, in some cases, may exceed that demanded. Furthermore, when the flow of current through the coils of the electric apparatus has nearly ceased, or has diminished to such an extent that special means for cooling it need no longer be used, there is no need of maintaining the circulation of the cooling medium; and, by my invention the circulation is at such times stopped automatically.

In the accompanying drawings, hereby annexed to and forming part of this specification, Figure 1, is a representation, partly diagrammatic, of a transformer cooled according to my invention and Fig. 2, is a modified form of motor-regulator which I may employ.

Therein, T is a transformer which may be of considerable capacity, and the larger its capacity the more need there will be for providing cooling arrangements when it is under load. The transformer is shown as surrounded by a casing, C, of iron. This casing may be made of any suitable material, dependent upon the position where the transformer is installed, and the character of the cooling medium passing through it: if the transformer is situated in a sheltered position, and air is used for cooling, the casing might be made of wood. The pipes P, P', P'', form a closed pipe system connecting the trans-

former-casing C, the cooling chamber or condenser R, and the pump F. The pump F is shown as operated by an electric motor M, whose armature coils form an induced or secondary winding on closed circuit, and whose inducing or field coils are shown at S, S, in the main line or circuit leading from an alternating current generator G to the transformer T. When no current flows in the coils S, S, that is, when the transformer T is doing no work, the motor M will not revolve; it is also evident that its rate of revolution is dependent wholly upon the amount of current flowing in the coils S, S, that is, the current going from the generator G to the transformer, and therefore that the circulation of the fluid through the pipes P, P', P², depends upon the flow of current in the primary coils of the transformer; the heating effect increases with the current flowing through the transformer coils. The motor M is arranged to increase its speed with increase of current, so that the desired circulation is effected through the transformer. The cooling medium, which may be water, oil, or any other suitable fluid, is shown as going to the reservoir R after passing through the transformer, thence to the pump, and again to the transformer, being used over and over again. If the coils of the transformer were so well insulated that water could be used instead of an insulating fluid, like oil, and the supply of water was abundant, of course no arrangements for cooling it for repeated use after it had passed through the transformer would be required. Or, instead of using a cooling liquid a blower, B, may be driven by the electric motor M and a cooling stream of air forced to the transformer through the pipe P³, shown partly in dotted lines, and out at P⁴, also shown in dotted lines.

Fig. 2 shows an indirect method of accomplishing the same result, or a method in which the flow of current to or from the transformer acts to stop, start, and regulate an auxiliary electric motor. Thus, the motor M is a direct current motor, the lines a, b, leading thereto receiving current from any suitable source. A leading wire to the transformer coils, primary or secondary, includes the coil S which, when energized, pulls upon a core K in opposition to a retractor or spring Z. The movement of the core K actuates a lever L and moves a switch governing the flow of current in the motor M; it may also vary the amount of a resistance H in the circuit of the motor, to vary its speed or power, and the motor M

may drive the pump F already mentioned, the blower B, or any similar apparatus. The motor M might of course be any kind of a motor, electric or not. It may be mentioned, also, that while a pipe system has been shown in the drawings illustrating the invention, such a system is not essential in all cases. For instance, a stream of air from the blower B might simply be directed against the transformer T, which would preferably be provided with openings or passages through which the air could circulate to convey away the heat.

Having thus described my invention, what I claim as new, and wish to protect by Letters Patent of the United States, is—

1. The method of cooling electric apparatus, which consists in supplying to such apparatus a flow of cooling fluid proportioned to the current passing therein.

2. The method of cooling transformers or other electric apparatus herein set out and described, which consists in forcing through such apparatus a flow of cooling fluid automatically proportioned to the current passing therein.

3. As a means of cooling electric apparatus, a pump, a motor actuating such pump and governed by the current in the apparatus to be protected, and a system of pipes including a source of fluid supply and connecting the pump with the apparatus to be cooled.

4. In combination, a transformer, a pipe leading therefrom, a pump supplying a cooling fluid to such pipe, an electric motor driven by the current passing in the transformer and arranged to operate the pump, and a source of fluid supply; all arranged and adapted to supply the cooling fluid at a rate proportioned to the flow of current in the transformer.

5. In combination, a transformer, a blower forcing air through such transformer, and means, substantially as described and set forth herein, adapted to actuate the blower at a rate dependent upon the current passing in the transformer.

6. In combination, a transformer, a blower forcing air through pipes leading to such transformer, and an electric motor driven at a rate dependent upon the current passing in the transformer, and adapted to operate the blower, substantially as described.

In witness whereof I have hereunto set my hand this 29th day of June, 1893.

WALTER S. MOODY.
